UNITED STATES PATENT OFFICE.

CHARLES M. DALY, GUSTAV A. WEIDHAAS, AND WILLIAM S. HENRY, OF NEW YORK, N. Y.

HYGIENIC EATING UTENSIL.

No. 910,914.

Specification of Letters Patent.

Patented Jan. 26, 1909.

Application filed February 18, 1908. Serial No. 416,626.

To all whom it may concern:

Be it known that we, CHARLES M. DALY and GUSTAV A. WEIDHAAS, residents of the city of New York, borough of Manhattan, in 5 the county and State of New York, and WILLIAM S. HENRY, a resident of the city of New York, borough of Bronx, in the county and State of New York, all citizens of the United States, have invented new and useful Improvements in Hygienic Eating Utensils, of 10 which the following is a full, clear, and exact description.

This invention relates to certain improvements in eating utensils especially adapted 15 for use at lunch counters and the like, and relates more particularly to a construction involving a plurality of utensils adapted to be dispensed from a suitable container, and sufficiently simple and inexpensive to manufacture as to permit of their being thrown 20 away after being used but once.

It is customary at various places, particularly saloons, where lunch is served free, to provide a few forks for the use of any who 25 may desire to partake of the food, and these forks are seldom, if ever, thoroughly cleaned and disinfected after each time they are used.

We contemplate by our invention the provision of a plurality of forks or other eating 30 utensils of such simplicity of construction and small cost of manufacture as to permit of their being thrown away after being used. In order to prevent their being used a second time and also in order to facilitate the dis- 35 pensing of the forks or the like to the user, as well as to maintain them clean until used, we form the forks of thin strips of wood connected together in series to form a band, the several forks being connected together by a 40 thin strip of frangible material, as, for instance, paper. The series or band is designed to be mounted within a suitable casing, whereby a fork may be readily separated from the band by the user and the remainder 45 of the band retained within the casing and protected from dust and dirt. Each patron in taking a fork from the roll knows that it has not been used before and that it is in a clean and sterilized condition. The patron 50 would not take forks from the table, as he would think that they had been used before and the proprietor would have no incentive to collect the forks left on the table or thrown on the floor, as the customers use only those 55 taken from the roll. Each fork or the band connecting them might carry any suitable

advertising matter printed thereon, but printed in a non-poisonous ink which would not interfere with the hygienic qualities of the fork. 60

Reference is to be had to the accompanying drawings, forming a part of this specification, in which similar characters of reference indicate corresponding parts in both the figures, and in which 65

Figure 1 is an end view of a container having mounted therein a roll of forks constructed and assembled in accordance with our invention; and Fig. 2 is a plan view of a portion of the band or roll. 70

In the specific construction illustrated, we provide a plurality of forks 10, each formed of a thin strip of wood of substantially uniform thickness and uniform width. Each wooden strip is provided with a reentrant 75 angle at one or both ends, so as to form tines or prongs 11, and the forks are all connected together in series to form a long band by one or more suitable strips 12 of thin paper or other frangible material. The forks are 80 pasted or glued to the strip 12 and the strip may be readily torn between adjacent forks. The band or strip of forks may be held within any suitable form of container, from which they may be dispensed, but, as illustrated, 85 we provide a suitable cylindrical casing 13 having a slot 14 therein and a hinged guide plate 15 for directing the forks to said slot. The casing may be mounted in any suitable supports 16 to hold the same stationary and 90 permit the band to be drawn therefrom.

In use, the dispensing container or casing is mounted adjacent the supply of food with suitable instructions as to the manner in which the forks are dispensed. The patron 95 when desiring a fork tears one off from the roll and after using the same may dispose of it as he pleases but he cannot return it to the roll. Thus, each and every patron is insured a clean and sterilized fork, which he knows 100 has never before been used.

Although the series of forks as illustrated are especially designed for use in a stationary container and in connection with a "free lunch" counter, yet it is evident that they 105 may be used by picnic parties and the like.

Having thus described our invention, we claim as new and desire to secure by Letters Patent:

1. In combination, a plurality of forks, 110 each formed of a flat stick of wood, and a band of flexible material permanently se-

cured to one side of each of said forks to hold them together in series closely adjacent each other, said band being separable into sections intermediate each two adjacent forks.

5. 2. In combination, a plurality of forks, each formed of a strip of wood having a re-entrant angle at one end thereof arranged in series and presenting oppositely - disposed substantially parallel surfaces, and means 10 extending along one of said surfaces and secured directly to each fork for connecting them together.
- 15 3. A band having the body thereof formed of a plurality of forks arranged adjacent each other in series and extending transversely of the band, and connecting means directly secured to each fork intermediate the ends thereof and flexible intermediate adjacent forks.
- 20 4. In combination, a plurality of forks each formed of a strip of wood of substantially uniform width and of substantially uniform thickness, and having a reentrant angle at one end thereof forming a plurality of tines 25 or prongs, and a strip of frangible material connecting said forks together in series.

5. A fork formed of a flat strip of wood of substantially uniform width and substantially uniform thickness and having a re-entrant angle at one end thereof forming a 30 plurality of tines or prongs.

6. In combination, a plurality of forks, each formed of a strip of wood of substantially uniform thickness, and a strip of frangible material secured to each of said forks to 35 connect them together in series to form a band and to permit of their ready separation.

7. A roll formed of a band of frangible material having a plurality of eating utensils glued or pasted thereto, each of said eating 40 utensils being formed of a strip of wood, and said band being separable into sections intermediate each two adjacent eating utensils.

In testimony whereof we have signed our names to this specification in the presence of 45 two subscribing witnesses.
